UNITED STATES PATENT OFFICE.

WILLIAM M. DOUCETTE, OF NEW YORK, N. Y.

DESIGN FOR A TIRE-TREAD.

59,069.

Specification for Design. Patented Sept. 20, 1921.

Application filed February 15, 1921. Serial No. 445,269. Term of patent 14 years.

To all whom it may concern:

Be it known that I, WILLIAM M. DOUCETTE, a citizen of the United States of America, residing at New York, county and State of New York, have invented a new, original, and ornamental Design for Tire-Treads, of which the following is a specification, reference being had to the accompa-

nying drawings, forming a part thereof, in which—

The figure is a plan view of a portion of a tire showing the design.

I claim:

The ornamental design for a tire-tread as shown.

WILLIAM M. DOUCETTE.
